UNITED STATES PATENT OFFICE.

CLARENCE L. TAYLOR, OF ALLIANCE, OHIO, ASSIGNOR TO THE MORGAN
ENGINEERING COMPANY, OF ALLIANCE, OHIO.

HYDRAULIC CRANE.

No. 805,038.

Specification of Letters Patent.

Patented Nov. 21, 1905.

Application filed October 8, 1904. Serial No. 227,668.

To all whom it may concern:

Be it known that I, CLARENCE L. TAYLOR, of Alliance, in the county of Stark and State of Ohio, have invented certain new and useful Improvements in Hydraulic Cranes; and I do hereby declare the following to be a full, clear, and exact description of the invention, such as will enable others skilled in the art to which it appertains to make and use the same.

My invention relates to an improvement in hydraulic cranes adapted more particularly for use in forge-shops, the object being to so mount the main hoist-cylinder that it will be free to oscillate in any direction, and hence capable of yielding or giving in the event the cylinder, piston, or load carried by the piston should come in contact with an object, and also permit the cylinder to give to accommodate itself to the lag of the load.

With these and other ends in view my invention consists in the parts and combinations of parts, as will be more fully explained, and pointed out in the claims.

In the accompanying drawings, Figure 1 is a view in side elevation of a section of a bridge showing my improvement thereon. Fig. 2 is a view in transverse section through the bridge, trolley, and main cylinder. Fig. 3 is an enlarged view through bridge, trolley, cylinder, and cylinder-mounting, part of the trolley and cylinder-mounting being in section. Fig. 4 is a view taken at right angles to Fig. 3, and Fig. 5 is a view in section on the line A A of Fig. 3.

1 represents an overhead traveling bridge propelled lengthwise its supporting-track-way 2 by the motor 3. This motor is geared up to shaft 4, running lengthwise the bridge-girders, and the shaft is provided at its ends with gear-wheels which mesh with larger gears 5 on shafts 6. These shafts 6 carry smaller gears 7, which mesh with the larger gears 8 on the axles of the track-wheels 9, the central flanges of which travel between the rails of track 2.

Mounted on rails 10, carried on top of the bridge-girders, is the traveling trolley 11. This trolley is a hollow casting having an open center, the sides or walls of which opening diverge downwardly, so as to permit the hoist-cylinder 12 to swing freely without colliding with the walls of the trolley.

Secured on top of the trolley and on opposite sides of the opening in the center thereof and in recesses or seats 13 formed therefor are the bearings 14, which latter are provided with teeth 15 near their outer edges and are plane and flat at their inner edges. Mounted on these bearings 14 is the rectangular rocking frame 16, provided with bearings 17, which latter rest on and engage the bearings 14 on the trolley. These bearings have plane surfaces 18 and toothed surfaces 19, corresponding to the plane and toothed surfaces of bearings 13, and their lower bearing-faces are formed in the arc of a circle to form rockers, the teeth on the two bearings preventing any creeping movement of the frame 16 on the trolley, lateral displacement being prevented by the seats 13, which also receive the contacting edge of the upper bearings 17, as clearly shown in Fig. 3. This rocking frame 16 is open at its center and is provided on its upper face with the parallel bearings 19^a, which latter are located at right angles to the bearings 17 and on opposite sides of the central opening in rocking frame 16. These bearings 19^a are flat and are toothed at their outer edges and form seats for the rocking bearings 20, carried by the rocking yoke 21. The bearings 20 are curved in the arc of a circle and are provided with plane surfaces to engage the plane surfaces of bearings 19^a and with toothed portions to engage the toothed portions of bearings 19^a. The intermeshing teeth of the bearings 19^a and rocker-bearings 20 prevent any creeping of the yoke on the frame in the direction of movement of the yoke, while the engagement of the guides 21, formed on opposite sides of the cylinder, (see Figs. 4 and 5,) prevent any lateral movement of the yoke. This yoke is provided with a central circular opening to receive the head 22 of cylinder 12, the upper end of the head being seated on the annular shoulder 23 of the yoke. The cylinder is therefore suspended from the yoke, and as the yoke has a rocking motion on the rocking frame and the latter a rocking motion on the trolley at right angles to the rocking motion of the yoke the suspended cylinder is free to swing in any direction, limited only in its movements by the size of the opening in the trolley.

Located within the cylinder 12 is the piston 24, the rod 25 of which passes through the lower end of cylinder and carries at its lower end the bracket 26, in which sheave 27 is mounted. This sheave is designed to carry an endless chain, which forms a supporting-loop for the ingot or forging or tool employed for manipulating the forging. Secured to or formed integral with the yoke 21 is the laterally-projecting platform 28, which carries an electric motor 29. The armature-shaft of this motor carries a pinion 30, which latter meshes with the gear-wheel 31, secured on the upper end of shaft 32. Shaft 32 passes through a bearing in the head of the cylinder 12 and through piston 24 and piston-rod 25, as shown in Fig. 2, and is provided at its lower end with a worm 33, which meshes with worm-wheel 34, mounted in a bearing carried by bracket 26. This worm-wheel 34 is fixed to a gear-wheel, which latter meshes with a gear wheel or teeth on sheave 27. It will thus be seen that by starting the motor 29 shaft 32 will be rotated and by means of the gearing described rotate the sheave 27 and the endless chain carried by the latter. The cylinder 12 is connected by a system of jointed pipes 35 with an accumulator or other source of water under compression, and by admitting water under piston 24 the piston and its load will be elevated and by permitting the water under the piston to escape the load will be lowered. If desired, the bracket 26, carrying sheave 27, may be mounted on roller-bearings, thus permitting the bracket carrying the sheave to be turned on the piston-rod. With this arrangement the load may be carried to any part of the shop covered by the movements of the bridge and trolley and may be raised, lowered, rotated, and turned so as to present any and all parts of the forging to the action of the hammer, and as the cylinder is connected to the trolley by a universal joint, which permits free swinging movement of the cylinder, the latter will give when the load collides with any other object and will give under the lagging movement of the load.

It is evident that many slight changes might be resorted to without departing from the spirit and scope of my invention. Hence I would have it understood that I do not wish to confine myself to the exact construction of parts herein shown and described; but,

Having fully described my invention, what I claim as new, and desire to secure by Letters Patent, is—

1. The combination with a support, of a rocking frame mounted on said support, a rocking yoke mounted on the frame and provided with a central opening, the bearings of the yoke being at right angles to the bearings of the frame, a cylinder seated on said yoke

and depending therefrom, and a piston in 65 the cylinder.

2. The combination of a traveling trolley, of a rocking frame mounted on the trolley, a rocking yoke mounted on the rocking frame and provided with a central opening, the 70 bearings of the yoke being at right angles to the bearings of the frame, and a cylinder seated on said yoke and depending therefrom.

3. The combination with a traveling 75 bridge, and a traveling trolley thereon, of a rocking frame mounted on the trolley, a rocking yoke mounted on the rocking frame and provided with a central opening, the 80 bearings of the yoke being at right angles to the bearings of the rocking frame, and a cylinder seated on said yoke and depending therefrom.

4. The combination with a traveling trolley having an open center, of a rocking 85 frame mounted on the trolley, a rocking yoke mounted on the rocking frame and having an open center, the bearings of the yoke being at right angles to the bearings of the frame, and a cylinder seated on the yoke and projecting through the frame and trolley.

5. The combination with a traveling trolley having an open center, of a rocking frame mounted on the trolley and having teeth engaging teeth on the trolley, a rocking yoke 95 mounted on the frame and having teeth engaging teeth on the rocking frame, the bearings for the yoke on the frame being at right angles to the bearings for the frame on the trolley, and a cylinder carried by the yoke. 100

6. The combination with a traveling trolley having an open center, of a rocking frame mounted thereon, a rocking yoke mounted on the frame, the bearings of the yoke being at right angles to the bearings of 105 the frame, a cylinder carried by the yoke, a motor also carried by the yoke, a piston, piston-rod, a sheave carried by the piston-rod, a shaft passing through the piston-rod, piston and cylinder, gearing connecting said 110 shaft and motor, and gearing connecting said shaft and sheave.

7. The combination with a support having oppositely-disposed straight bearings, of a frame having oppositely-disposed curved 115 rockers, and straight bearings, the latter being at right angles to the bearings on the support, a yoke having curved rockers resting on the straight bearings of the frame, and a cylinder carried by said yoke. 120

8. The combination with a support having oppositely-disposed straight bearings provided with upwardly-projecting teeth, of a frame having curved rockers provided with teeth engaging the teeth on the bearings, and 125 also provided on its upper face with straight bearings having projecting teeth, the bearings on the frame being at right angles to the

rockers, a yoke having curved rockers provided with depending teeth meshing with the teeth on the bearings on the frame and a cylinder carried by said yoke.

5 9. The combination with a traveling trolley, of a rocking yoke carried by said trolley, a cylinder carried by the yoke, a motor also carried by the yoke, a piston and piston-rod, a sheave carried by the piston-rod, a shaft 15
10 passing through the piston, piston-rod and

cylinder, gearing connecting said shaft and motor, and gearing connecting the shaft and sheave.

In testimony whereof I have signed this specification in the presence of two subscribing witnesses.

CLARENCE L. TAYLOR.
